UNITED STATES PATENT OFFICE.

MAX M. HESSER, OF CHICAGO, ILLINOIS; BERTHA HESSER EXECUTRIX OF SAID MAX M. HESSER, DECEASED.

WASHLINE-RACK.

1,035,825.

Specification of Letters Patent. Patented Aug. 13, 1912.

Application filed June 30, 1911. Serial No. 636,272.

To all whom it may concern:

Be it known that I, MAX M. HESSER, a citizen of the United States, residing at Chicago, in the county of Cook and State 5 of Illinois, have invented a new and useful Washline-Rack, of which the following is a specification.

This invention relates to rope of cord holders and more particularly to clothes line 10 holders.

The object of the invention is to provide a simple and efficient device which is adapted to hold a clothes line and which is provided with means for looping the clothes 15 line thereon so that the same can not become unrolled.

Further objects of this invention will appear as the following specific description is read in connection with the accompanying 20 drawing, which forms a part of this application, and in which the figure is a perspective view of the device.

In the specific embodiment of the invention as illustrated herein, a single strand of 25 wire 1 having its terminals connected in a handle C is bent into the required form. Each end of the strand is bent laterally and then at right angles to the lateral bend inwardly toward the handle so as to form retaining members 2. These retaining portions 30 are connected with line supporting portions 3 which are connected to similar retaining portions 4 and 5, the latter through

an inwardly extending loop A and the former through a double loop B. The loop 35 A is adapted to receive the knotted end of the cord so as to hold the same while it is being wound up upon the portions 3. The inwardly projecting portion of the double loop B is adapted to receive a loop in the 40 clothes line or other cord being wound upon the device so as to prevent the cord from unwinding therefrom. A loop or half hitch may be taken around this inwardly projecting portion of the loop B or the cord may 45 be entered in between the legs of the same.

What I claim as new is:—

A clothes line reel constructed of a single strand of wire, the ends of which are bent back upon themselves to produce retaining 50 members and then bent at right angles to the bent back part to produce parallel winding portions, said strand having the ends bent back at right angles and then back upon themselves to produce other retaining 55 members, a handle member securing the terminals of strand together, an inwardly extending loop formed in one of the winding portions and having a relatively wide mouth, and an outwardly extending loop 60 formed in the opposite winding portion and having a restricted entrance.

MAX M. HESSER.
